UNITED STATES PATENT OFFICE.

JAMES L. EAST, OF DENVER, COLORADO.

BEET-TOPPER.

1,373,872.

Specification of Letters Patent.

Patented Apr. 5, 1921.

Application filed March 25, 1920. Serial No. 368,780.

To all whom it may concern:

Be it known that I, JAMES L. EAST, a citizen of the United States, residing at Denver, in the county of Denver and State of Colorado, have invented certain new and useful Improvements in Beet-Toppers, of which the following is a specification.

This invention relates to beet topers and its main object resides in providing a light, simple and every effective device which may be readily operated by any suitable propelling means to sever the tops of sugar beets and the like, prior to their removal from the ground.

Another object of the invention is to provide a device of the type above mentioned which is particularly adapted for operation in connection with a beet-harvesting machine having the usual appliances for lifting the beets out of the ground.

Another object is to provide in connection with the topping device, improved means for moving the severed beet tops out of the path of the digging appliances, and still further objects reside in providing details of construction and novel arrangements of parts all of which contribute to the effective operation of the topper and to economy in its construction.

With these objects in view, my improved beet-topper consists in the construction and combinations of parts hereinafter to be more fully described and shown in the preferred form of the invention, in the accompanying drawings in the various views of which like parts are similarly designated, and in which—

Figure 1 is a sectional plan view of the improved topping device;

Fig. 2, a side elevation thereof;

Fig. 3, a section taken along the line 3—3, Fig. 1, and

Fig. 4, an enlarged section along the line 4—4, Fig. 1.

Referring to the drawings by numerical reference characters, my improved beet topper consists of a frame 5 of structural metal which may be attached to a beet harvesting machine, forward of its digging appliances or to any other machine or device which is suitable for drawing the topper over the field to be harvested.

A sled 6 composed of two parallel runners 7 connected by arches 8 is suspended from

the frame by coiled springs 9 attached at 55 the upper portions of the arches.

Each runner consists of a longitudinally extended loop 10 which for simplicity in construction is composed of two sections 12 and 13 connected by bolts 14. The bolts are 60 also employed to rigidly connect the runners to the arches which to this end are provided with laterally projecting feet 15.

The runners are provided with transverse slots 16 through which the bolts are passed 65 thereby permitting of varying the distance between them.

The upper sections 13 of the runners are extended forwardly to provide upwardly curving draw bars 17 by which the sled 70 is pivotally connected to the frame.

This connection is established through the medium of a yoke 18 which is suspended from the frame to move about a vertical axis in a bearing 19 and which is branched at 75 its lower end for the pivotal connection of the draw bars. The latter are to this end provided with eyes 20 into which the horizontally aligned ends of the arms of the yoke are loosely fitted.

The sections of the runners have central transverse slots 21 through which are passed bevel headed bolts 22 upon which the cutters 23 of the device are rotatably supported.

The cutters which are mounted within the 85 loops of the runners, are of circular disk-like form and have oppositely extending hubs 24 of different heights through which the bolts extend.

This construction permits of varying the 90 distance of the cutters above the surface over which the sled is moved by merely reversing their position in the loops.

Rigidly secured to the draw-bars are shovels 25 which extend forwardly of the cutting 95 disks to clear the ground for the passage of the runners.

Suspended from the frame rearwardly of the sled, is an element which operates to move the severed beet tops to one side of the 100 machine for the purpose of clearing the ground for the operation of the digging appliances on the harvesting machine with which the topper is connected.

This element consists of a drum 26 provided with a number of longitudinally extended rakes 27 the teeth of which are curved. The drum is rotatably mounted at the lower

ends of hangers 28 which are connected to the frame at non-alined points to place the axis of rotation of the drum slantingly with relation to the direction in which the sled 5 is moved in the operation of the machine.

The drum is rotatively mounted in boxes 29 by oppositely extending trunnions 30 and these boxes are slidable on the before-mentioned hangers 28 and are normally supported upon heads 31 at the lower ends thereof.

Springs 32 coiled around the hangers between the boxes and superposed collars 33 permit of a yielding upward movement of 15 the drum when its rakes engage obstructive matter.

The rotary cutting disks adjoin peripherally intermediate of the runners of which the sled is composed so that when the runners move at opposite sides of a row of beets the cutting edges of the disks will engage the portions thereof extending above the surface of the ground. The top sections of the runners are extended laterally inwardly 25 and bent upwardly to provide converging ledges 34 which in the operation of the machine ride across the tops of the beets and thereby gage the distance from their crowns at which the tops are severed.

In the operation of the machine the frame 30 is connected to the harvesting machine or other propelling device by any suitable means and the rotary top-deflecting element is connected to a rotating part of the same 35 by means of a belt or chain 35 running upon a sprocket wheel or pulley 36 at the end of one of its trunnions.

During movement of the sled at opposite sides of a row of beets to be harvested, the shovels 25 clear the ground for the passage 40 of the runners and the circular cutting disks coöperate to sever the tops of the beets.

The gages 34 on the runners determine the distance at which the tops are severed 45 from the roots and the rotating rakes 27 move the severed tops to one side of the machine out of the path of the digging appliances of a harvesting machine.

It will be seen that the pivotal and flexible connections between the frame and the sled 50 permit of an up and downward movement of the runners and the therewith connected knives when the gages engage beets protruding at different heights above the surface of the ground.

The connections furthermore allow the sled to pass over obstructive matter not removed by the action of the shovels and the pivotal connection of the yoke with the frame 60 permits of a lateral deflection of the sled to compel it to engage all the beets in a row irrespective of their alinement.

The slotted connection of the runners with the arches by which they are connected and

the slotted connection of the knives with the runners allow of adjustment of the parts to take up wear or to adapt the machine for effective operation under varying conditions and the yielding connection of the top-deflecting element with the frame permits of 70 its riding across obstructive matter without breakage or deformation of its rakes.

Having thus described my improved beet topper in the most practical form at present known to me, I desire it understood 75 that modifications in the construction and arrangements of its parts may be made without departing from the spirit of the invention.

What I claim and desire to secure by Letters-Patent is:

1. A beet topper comprising a sled composed of connected runners, and rotary cutting disks reversibly mounted on the runners and each having two hubs of different 85 heights.

2. A beet topper comprising a frame, a sled having a universal movement thereon, and a cutting element on the sled.

3. A beet topper comprising a frame, a sled, flexible means connecting the sled with the frame, and a cutting element on the sled.

4. A beet topper comprising a frame, a sled pivoted thereon, a flexible connection between the sled and the frame, and a cutting element on the sled. 95

5. A beet topper comprising a frame, a sled pivoted thereon for movement about vertical and horizontal axes, and a cutting element on the sled.

6. A beet topper comprising a frame, a sled pivoted thereon for movement about vertical and horizontal axes, a flexible connection between the sled and the frame, and a cutting element on the sled. 100

7. A beet topper comprising a frame, a yoke pivoted thereon to move about a vertical axis, a sled pivoted on the yoke to move about a horizontal axis, and a cutting element on the sled. 105

8. A beet topper comprising a frame, a yoke pivoted thereon to move about a vertical axis, a sled pivoted on the yoke to move about a horizontal axis, a flexible connection between the frame and the sled, and a cutting element on the sled. 110

9. A beet topper comprising a frame, a sled composed of runners having forwardly extended draw bars, a pivotal connection between the draw bars and the frame, and a cutting element on the sled. 115

10. A beet topper comprising a frame, a sled composed of runners having forwardly extended draw bars, a pivoted yoke on the frame, in pivotal connection with said draw bars, and a cutting element on the sled. 120

11. A beet topper comprising a frame, a sled composed of runners having forwardly

extended draw bars in connection with the frame, shovels on said draw-bars, and a cutting element on the sled.

12. A beet topper comprising a frame, a sled composed of runners and arches connecting the same, springs connecting the arches to the frame, a pivotal connection between the sled and the frame, and a cutting element on the sled.

10 13. A beet topper comprising a sled, a cutting element thereon, and rearward of the sled, an element adapted for moving severed beet tops to one side, and yieldably mounted for up and downward motion.

15 14. A beet topper comprising a sled, a cutting element thereon, and rearward of the sled, an element for moving severed beets to one side, composed of a rotary drum having a series of longitudinally ex-

20 tended rakes.

15. A beet topper comprising a frame, a sled composed of runners and arches connecting the same, flexible connections between the arches and the frame, a pivotal connection between the sled and the frame, and a cutting element on the sled.

25 16. A beet topper comprising two normally rigidly connected runners, a pair of coöperating cutting disks rotatably mounted on said runners, and means to adjust the

distance between the runners whereby to vary the coöperative relation of the cutting disks.

17. A beet topper comprising two normally rigidly connected runners, a pair of 35 coöperating cutting disks rotatably mounted on said runners, and means to adjust the position of the axes of rotation of the disks on the runners, whereby to vary the distance between them.

18. A beet topper comprising a sled mounted for upward motion and including two connected runners which at their inner edges have ledges placed with relation to each other to lift the sled by engagement 45 with the top of a beet in the path thereof, and rotary cutting disks mounted on the runners to coöperatively sever the tops of the beets.

19. In a beet topper, a sled composed of 50 connected runners each comprising a draw-bar, and a strap having upwardly bent end portions fastened at the under side thereof, and coöperating cutting disks rotatably mounted in the spaces, between the draw- 55 bars and the respective straps of the runners.

In testimony whereof I have affixed my signature.

JAMES L. EAST.
